CLAIM

I claim the ornamental design for a knitting crochet hook, as shown and described.

DESCRIPTION

FIG. 1 is a front view of a knitting crochet hook showing my new design;

FIG. 2 is a left side view of the same crochet hook, the right side view being symmetrical to the left side view;

FIG. 3 is a rear view of the same crochet hook;

FIG. 4 is a top plan view of the same crochet hook;

FIG. 5 is a bottom view of the same crochet hook;

FIG. 6 is a sectional view of the same crochet hook taken along lines 6—6 in FIG. 1; and,

FIG. 7 is a sectional view of the same crochet hook taken along lines 7—7 in FIG. 1.
